Primary Examiner — Mojtaba Tehrani(74) *Attorney, Agent, or Firm* — Cabello Hall Zinda,
PLLC(57) **CLAIM**

The ornamental design for a modular shooting rest, as shown and described.

DESCRIPTION

FIG. 1 is a first perspective view of a modular shooting rest; FIG. 2 is a second perspective view thereof;

FIG. 3 is a back view thereof;

FIG. 4 is a front view thereof;

FIG. 5 is a top view thereof;

FIG. 6 is a bottom view thereof;

FIG. 7 is a side view thereof; and,

FIG. 8 is an opposite view thereof.

The broken lines in the drawings show unclaimed portions of the modular shooting rest and form no part of the claimed design.

1 Claim, 4 Drawing Sheets(56)
